United States Patent Office

Des. 232,240

Patented July 30, 1974

232,240

PLAYGROUND CLIMBER

Nancy Reed Markusen, Grand Forks, N. Dak., assignor
to University of Idaho Research Foundation, Moscow,
Idaho

Filed May 30, 1972, Ser. No. 258,222

Term of patent 14 years

Int. Cl. D21—01

U.S. Cl. D34—5 H

FIG 1

FIG 2

FIG 4

FIG 3

FIG. 1 is a perspective view of a playground climber showing my new design;

FIG. 2 is a side elevational view;

FIG. 3 is a top plan view, the bottom of the unit being plain and unornamented; and

FIG. 4 is an end elevational view.

I claim:

The ornamental design for a playground climber, as shown and described.
